LIQUEFACTION AND GAS BOOSTING SYSTEM

Oscar E. Gammill, Jr., Dallas, Tex., assignor to
Carrier Corporation, Syracuse, N. Y., a corpora-
tion of Delaware

Application May 30, 1944, Serial No. 538,099

5 Claims. (Cl. 62—175.5)

1

This invention relates to a method of and means for handling gases for the purpose of recovering constituents therefrom and thereafter reinjecting residual gases into a well or utilizing the same in an industrial process.

The general object of the invention is to recover, on an efficient basis, desired constituents from a gas stream and then to boost the residual constituents to a desired degree, the boosted constituents then being returned to a gas well or utilized as desired.

A feature of the invention resides in the subjection of a stream of gas to a series of stages of refrigeration to the end that recovery of desired constituents is effected at each of the stages.

Another feature of the invention covers the use of a plurality of interchangers served by a plurality of refrigeration systems. The interchangers subject a stream of gas to progressively lower temperatures and simultaneously subject a return stream of gas to progressively higher temperatures. The first stream serves to provide recovered constituents as a result of condensation at progressively lowered temperature levels. The return stream serves a two-fold purpose: (1) to effect condensation of compressed gases in the different stages of compression of said refrigeration systems; and (2) to effect more efficient interchange in the constituent recovery steps aforesaid.

Other features and advantages of the applicant's recovery and booster system will be more apparent from the following written description of one form of the invention to be read in connection with the accompanying drawing showing a diagrammatic arrangement illustrative of the intended application without regard to specific design or structure of the various parts.

Considering the drawing, numeral 1 designates in fragmentary diagrammatic form, a gas well. While the invention is being described in connection with gas drawn from a well, it also applies to a stream of gas, hydrocarbon constituents, or other combination of gaseous compounds drawn from any desired source. The stream of gas flows from well 1 through pipe line 2 to a series of interchangers 3, 4 and 5. It will be understood that depending upon the application of the invention, any required number of interchangers of desired capacity and arrangement may be employed. Such interchangers contain a first series of interchanger coils 6, 7 and 8. While such coils may in practice, at least as to one or more of them, be served by well water, brine from any desired source, cooling medium from a spray pond or cooling tower, or the like, the interchangers illustrated are in this instance served by a plurality of refrigeration systems. In essence, coils 6, 7, and 8 constitute evaporator elements forming part of the re-

2

spective refrigeration cycles in which they are located.

Thus, refrigerant compressor 9, preferably a centrifugal compressor driven by a steam turbine, discharges refrigerant at a desired pressure to condenser 10, the refrigerant then proceeding through interchanger 11, evaporator coil 6 and back in gaseous state to the compressor. Similarly, stage 2 of refrigeration includes 10 compressor 12, condenser 13, interchanger 14, and evaporator coil 7. Stage 3 of refrigeration similarly includes compressor 15, condenser 16, interchanger 17, and evaporator 8. The various stages of refrigeration are designed so that the suction temperature in coils 6 corresponding to the suction pressure will be higher than that in coil 7 which in turn will be higher than that in coil 8. The compressors are designed to handle refrigerants, as desired, and are equipped with driving elements capable of providing desired temperatures in the respective evaporators 6, 7 and 8.

The stream of gas from pipe line 2 will first enter interchanger 3 and partial recovery due to the action of evaporator coil 6 upon the gas stream will result in condensed or recovered constituents being precipitated and removed from the interchanger through recovery line 18. The remaining constituents proceed from interchanger 3 through line 19 to interchanger 4 where the temperature of the evaporator, as pointed out, is lower. As a result further recovery of constituents is accomplished and the condensate is similarly withdrawn through line 20. 30 The process is repeated in interchanger 5 with the condensate forwarded to pump 25. Undesirable non-condensable gases are removed through purge line 24 as illustrated.

When the remaining constituents leave interchanger 5 they are at a comparatively low temperature, in many instances at minus 100° F. or lower. This will vary depending upon the nature of the gases handled. In any event, the temperature is so low that the remaining constituents 45 leaving interchanger 5 contain at least some matter in liquid state. Fluid pump 25 can, accordingly, effectively boost the remaining constituents to a desirable higher pressure. The result is that the gases will be boosted to a desirable higher pressure for reinjection into the gas well, as may be necessary. Thus, if gas from well 1 flows at a pressure of 2500 pounds per square inch, it is necessary that the reinjected gas be discharged into the ground at a higher pressure and this, as described, is accomplished by applicant effectively in his provision of a system which converts the gas delivered from the well (or other source) to a fluid state which can practically be handled by a liquid pump and booster to a desired higher pressure level. The

pressure applied by pump 25 to the liquid prevents substantial volatilization thereof during its passage through interchangers 17, 14 and 11.

When the remaining constituents leave pump 25 they enter trap 26 and then follow two paths. In a first path, gas from the trap feeds through line 27, coil 28 in interchanger 5, line 29, coil 30 in interchanger 4, line 31, coil 32 in interchanger 3, and back to the ground through line 33 to maintain pressure therein or, as described above, the gas may be utilized as desired without being returned to the well. Therefore, it will be seen that the gas in its course from trap 26 is progressively elevated in temperature as it proceeds through interchanger 5, 4 and 3, thus making for greater efficiency in the interchange action throughout the system. The gas being discharged into the ground through line 33, is at a moderate difference in temperature from that leaving from the ground 20 through line 2.

In the other course, liquid from trap 26 flows through interchangers 17, 14 and 11 of the respective stages of refrigeration with the result that progressive sub-cooling of the refrigerant from condensers 16, 13 and 10 is accomplished, with the flow from interchanger 11, in liquid state, proceeding to storage tank 34.

The recovered constituents flowing through lines 18, 20, 21 and 33 are made available by simple liquefaction without recourse to other and more expensive and complicated refining operations. The recovered constituents may then be simply fractionally distilled to obtain the products contained therein such as are contained in natural gasoline.

Since various changes may be made without departing from the spirit of the invention, no limitation is intended with respect to the disclosure in the specification and drawing but only as indicated in the appended claims.

I claim:

1. A system for recovering constituents from gases and boosting residue therefrom in liquefied condition to a higher pressure which comprises a first series of interchangers, a series of refrigeration systems, each refrigeration system including a compressor, a condenser and an evaporator, the evaporators of the refrigeration systems being disposed in said interchangers, a second series of interchangers interposed in the lines connecting the condensers and evaporators of the refrigeration systems, each interchanger of the second series admitting refrigerant from a condenser of said refrigeration systems, a series of return flow heat exchange coils in said first series of interchangers, means for routing gases through said first series of interchangers in one direction, a pump for boosting the pressure of constituents leaving the last interchanger of the first series, a trap for separating gases from the boosted liquid constituents, means for routing the separated gases to the return flow heat exchanger coils in said first series of interchangers in the opposite direction and means for routing boosted constituents in liquefied form through said second series of interchangers in heat exchange relation with refrigerant therein.

2. A method of recovering constituents from gases flowing from a well which consists in passing the gases from the well in heat exchange relation with a cooling medium to liquefy some portion of said gases, removing the recovered liquefied constituents, passing the remaining gases in heat exchange relation with a second

cooling medium at a temperature lower than the temperature of the first cooling medium to recover in liquid form some portion of said gases, removing the recovered liquefied constituents, passing the remaining gases in heat exchange relation with a third cooling medium at a temperature lower than the temperature of the second cooling medium to liquefy a portion of said gases, boosting the discharge from said third interchanger to a desired higher pressure, separating the liquid from the gases, passing the liquid in heat exchange relation with the cooling mediums in reverse order to sub-cool the mediums, and routing the separated gases in heat exchange relation with the original gases.

3. A method of recovering constituents from gases flowing from a well which consists in passing gases from the well through a plurality of cooling stages in heat exchange relation with a separate cooling medium in each stage to liquefy a portion of the gases in each stage, removing the recovered liquefied constituents from each stage, boosting the fluid from the last stage to a desired higher pressure, separating the liquid from the gases, and passing the separated liquid in heat exchange relation with the cooling mediums in said stages to sub-cool the mediums prior to disposal in heat exchange relation with the gases.

4. A method of recovering constituents according to claim 3 in which the separated gases are routed in heat exchange relation with original gases passing through said cooling stages.

5. A system for recovering constituents from gases and boosting residue therefrom in liquid condition to a higher pressure, which comprises a series of interchangers through which the gas is passed in heat exchange relation with a cooling medium, means for supplying cooling medium to said series of interchangers, a second series of interchangers, means for passing cooling medium through said second series of interchangers, means for routing gases through said first series of interchangers in one direction, a pump for boosting the pressure of constituents leaving the last interchanger of the first series, a trap for separating gases from the boosted liquid constituents, and means for routing boosted liquid constituents through said second series of interchangers to sub-cool cooling medium supplied to the first series of interchangers.
